UNITED STATES PATENT OFFICE

WILLIAM H. ROSE, OF JERSEY CITY, NEW JERSEY

CONTAINER COVER

Application filed December 11, 1925. Serial No. 74,751.

My invention relates to container covers and processes for producing the same and refers particularly to covers capable of hermetically sealing containers and which are so constructed as to be readily opened and processes for producing the same.

The object of my invention is a metallic container cover capable of being readily attached to a container, and so constructed that its plurality of hermetically sealed members may be readily separated when it is desirous of obtaining access to the container contents.

Container covers of the character described, and especially those adapted for use with preserved food products, must be absolutely air-tight even under considerable outward pressure, and must be capable of being readily opened when desired. They should also be economic in construction in both process of production and amount of material employed.

The device of my invention possesses all of these desirable properties and presents an economic and efficient and hermetically sealed cover for containers.

My device comprises a flanged central member and a flanged outer ring member, the flanges of the two members to be folded over contra-wise with respect to each other and abuttable upon each other to form an air tight jointure under usage but capable of ready disjointure when desired.

The several steps of production of my device, and the device itself, are fully explained in this specification with its accompanying drawings which will indicate the usefulness and effectiveness of my device.

In the accompanying drawings illustrating one form of the device of my invention, similar parts are designated by similar numerals.

Figure 1 is a top plan view of one form of my device.

Figures 2, 3, 4 and 5 are vertical cross-sections illustrating successive steps in the production of the device of Figure 1, Figure 5, showing the finished cover attached to a can or container.

The particular form of the device of my invention shown in the accompanying draw-

ings comprises two removably attached members 10 and 11.

The annular central member 10 has a downwardly extended flange 12, and the outer ring member 11 has an upwardly extended annular flange 13 forming an opening 14 of less diameter than the diameter of the central member 10.

The formation of the completed cover is as follows:—The members 10 and 11 are positioned as shown in Figure 2, and a proper cementing or sealing, material 15 introduced between the two flanges 12 and 13. The flange 12 is then spun inwardly and the flange 13 is spun outwardly, as shown in Figure 3 until the two members 10 and 11 and their respective flanges 12 and 13 have assumed the positions shown in Figure 4. The overlapped flanges 12 and 13 are then subjected to pressure forcing them together into closer contact and more secure jointure, as shown in Figure 5. The two flanges are thus folded contra-wise in abutment upon each other, the central member flange abutting upon the outer face of the outer member and the outer member flange abutting upon the inner face of the central member. The cover can then be permanently attached to a can, or receptacle, 16 by any proper means.

In order to open the cover, thus formed, a pointed flat instrument 17, as a screw driver, chisel or other suitable device, is forcibly inserted between the flange 12 and the member 11, and by raising the same, the overlapped flanges are displaced from their sealing position, allowing of the removal of the central member 10 from the ring member 11, thus exposing the contents of the receptacle through the opening 14.

Another suggested means of opening the cover is to spot weld a ring 18 to the central member 10 and near the outer edge thereof, so that an upward pull upon the ring will cause a disengagement of the abutting flanges 12 and 13. The ring 18 may be hinged at 19, as shown, thus allowing it to be flush with the cover when not in use.

The two flanges are thus folded contra-wise in abutting position upon each other, the central member flange abutting upon the

outer face of the outer member and the outer member flange abutting upon the inner face of the central member.

It is to be noted that any outward pressure brought to bear against the underside of the cover will have a tendency to force the flanges 12 and 13 still further into their respective overlapped positions, thus increasing the binding and sealing force.

10 I do not limit myself to the particular size, shape, number, arrangement or material of parts as shown and described as these are given simply as a means for clearly describing the device of my invention and the process of producing the same.

15 What I claim is:—

1. In a removable container cover, in combination, a flanged annular central member, and an outer flanged member having an annular opening therein, the two flanges being folded contra-wise upon each other and abutting upon each other forming a hermetically sealed jointure between the two members, the central member being positioned externally of the outer member whereby lever movement of an instrument positioned beneath the folded portion of the central member and resting upon the edge of the device adjacent to the cover will cause the separation of the central member from the outer member.

2. In a removable container cover, in combination, an annular central member, and an outer member having an annular opening therein, the outer portion of the central member and the opening portion of the outer member being folded contra-wise upon each other forming a hermetically jointure, the central member being positioned externally of the outer member whereby lever movement of an instrument positioned beneath the folded portion of the central member and resting upon the edge of the device adjacent to the cover will cause the separation of the central member from the outer member.

3. In a removable container cover, in combination, an annular central member, a flange carried by the outer portion of the central member, an outer member having an opening therein and a flange carried by the opening portion of the outer member, the flanges being folded contra-wise upon each other forming an air-tight jointure, the central member being positioned externally of the outer member whereby lever movement of an instrument positioned beneath the folded portion of the central member and resting upon the edge of the device adjacent to the cover will cause the separation of the central member from the outer member.

4. In a removable container cover, in combination, an annular central member, a flange carried by the outer portion of the central member, an outer member having an opening therein, a flange carried by the opening por-

tion of the outer member, the flanges being folded contra-wise upon each other forming an air tight jointure and a cementitious material between the folded flanges, the central member being positioned externally of the outer member whereby lever movement of an instrument positioned beneath the folded portion of the central member and resting upon the edge of the device adjacent to the cover will cause the separation of the central member from the outer member.

5. In a removable container cover, in combination, a flanged annular central member, and an outer flanged member having an annular opening therein, the two flanges being folded contra-wise upon each other and abutting upon each other, the central member flange abutting upon the outer face of the outer member and the outer member flange abutting upon the inner face of the central member, the central member being positioned externally of the outer member whereby lever movement of an instrument positioned beneath the folded portion of the central member and resting upon the edge of the device adjacent to the cover will cause the separation of the central member from the outer member.

6. In a removable container cover, in combination, an annular central member, and an outer member having an annular opening therein, the outer portion of the central member and the opening portion of the outer member being folded contra-wise upon each other, the central member flange abutting upon the outer face of the outer member and the outer member flange abutting upon the inner face of the central member, the central member being positioned externally of the outer member whereby lever movement of an instrument positioned beneath the folded portion of the central member and resting upon the edge of the device adjacent to the cover will cause the separation of the central member from the outer member.

7. In a removable container cover, in combination, an annular central member, an outer member having an annular opening therein, the outer portion of the central member and the opening portion of the outer member being folded contra-wise upon each other, the central member flange abutting upon the outer face of the outer member and the outer member flange abutting upon the inner face of the central member and a cementitious material between the folded flanges, the central member being positioned externally of the outer member whereby lever movement of an instrument positioned beneath the folded portion of the central member and resting upon the edge of the device adjacent to the cover will cause the separation of the central member from the outer member.

8. In a removable container cover, in com-

bination, an annular central member, a flange carried by the outer portion of the central member, an outer member having an opening therein and a flange carried by the opening portion of the outer member, the flanges being folded contra-wise upon each other, the central member flange abutting upon the outer face of the outer member and the outer member flange abutting upon the inner face of the central member, the central member being positioned externally of the outer member whereby lever movement of an instrument positioned beneath the folded portion of the central member and resting upon the edge of the device adjacent to the cover will cause the separation of the central member from the outer member.

Signed at New York City, in the county of New York and State of New York this 20 7th day of December, 1925.
